UNITED STATES PATENT OFFICE.

EDWIN I. GOLDING, OF NEW YORK, N. Y.

DESIGN FOR A TEXTILE FABRIC OR SIMILAR ARTICLE.

Application filed November 13, 1922. Serial No. 4,281. Term of patent 3½ years.

To all whom it may concern:

Be it known that I, EDWIN I. GOLDING, a citizen of the United States, and a resident of 420 Riverside Drive, in the county of New York, city and State of New York, have invented a new, original, and ornamental Design for Textile Fabric or Similar Article, of which the following is a specification, reference being had to the accompanying drawing, forming part of this specification.

The figure is a plan view of a piece of dress fabric embodying my design.

I claim:

The ornamental design for a textile fabric or similar article as shown.

In witness whereof, I have hereunder signed my name this 4th day of October, 1922.

EDWIN I. GOLDING.
